UNITED STATES PATENT OFFICE.

FREDERICH W. G. BOETTCHER, OF DETROIT, MICHIGAN.

DESIGN FOR A TOY.

SPECIFICATION forming part of Design No. 33,666, dated December 4, 1900.

Application filed October 25, 1900. Serial No. 34,399. Term of patent 3½ years.

To all whom it may concern:

Be it known that I, FREDERICH W. G. BOETTCHER, a citizen of the United States, residing at Detroit, in the county of Wayne and State of Michigan, have invented and produced a new and original Design for a Toy; and I do hereby declare the following to be a full, clear, and exact description of the same, reference being had to the accompanying drawings, forming a part thereof.

In the accompanying drawings, Figure 1 is a perspective view of a toy embodying my design, and Fig. 2 is a side elevation of the same.

The leading feature of my design consists of a toy having a body or handhold portion which is approximately round in cross-section and having a smooth unbroken continuous outline and formed with a longitudinally-extending projecting end which is approximately round in cross-section and has a

gradual uniform taper from its inner to its outer extremities.

1 in the drawings represents the handle or body portion, which is approximately round in cross-section and has a smooth unbroken continuous outline and formed with a longitudinally-extending projecting end 2, which is approximately round in cross-section and has a gradual taper from its inner to its outer extremities.

Having now described my invention, what I claim as new, and desire to secure by Letters Patent, is—

The design for a toy, substantially as herein shown and described.

In testimony whereof I hereunto affix my signature in presence of two witnesses.

FREDERICH W. G. BOETTCHER.

Witnesses:

LORENZO L. PULFORD,
FREEMAN W. WILCOX.
